ALBERT W. W. MILLER, OF SOUTH ORANGE, NEW JERSEY, AND GEORGE P. McDONNELL, OF ST. LOUIS, MISSOURI, ASSIGNEES TO AMERICAN ELECTRIC COMPANY, OF EAST ORANGE, NEW JERSEY, A CORPORATION OF NEW JERSEY.

DEVICE FOR SECURING INCANDESCENT-LAMP FILAMENTS TO LEADING-IN WIRES.

SPECIFICATION forming part of Letters Patent No. 758,328, dated April 26, 1904.

Application filed July 8, 1903. Serial No. 164,116. (No model.)

To all whom it may concern:

Be it known that we, ALBERT W. W. MILLER, residing at South Orange, New Jersey, and GEORGE P. McDONNELL, residing at St. Louis, Missouri, citizens of the United States, have jointly invented a certain new and useful Improvement in Devices for Securing Incandescent-Lamp Filaments to Leading-In Wires, of which the following is a full, clear, and exact description, such as will enable others skilled in the art to which it appertains to make and use the same, reference being had to the accompanying drawings, forming part of this specification, in which—

15 Figure 1 is a top plan view, partly broken away, illustrating our improved device. Fig. 2 is a vertical sectional view. Fig. 3 is an enlarged front elevational view of a pair of co-operating clamps. Fig. 4 is a side elevational view of the same, and Fig. 5 is a top plan view of the same.

This invention relates to new and useful improvements in devices for securing incandescent-lamp filaments to the leading-in wires, 25 the object being to mount the filament and leading-in wires in such fixed relation to each other that the end portions thereof may be secured or connected together, the parts being firmly held in fixed position until the permanent connection thereof.

The device consists of a traveling carrier having mounted thereon vise-clamps, preferably in the form of spring-jaws, in which the parts to be connected are held. The operator 35 adjusts the ends of the wires to be connected and after applying thereto a suitable paste moves the traveling carrier onward, giving the paste time to harden, during which hardening process the wires are in contact with each other and bear a fixed relation to each other. The vise-clamps referred to are in pairs, one clamp of each pair being preferably in vertical alinement with its companion. One clamp is designed to hold the carbon filament, and its companion is designed to hold the leading-in wires. One or both clamps is

preferably universally adjustable, means being provided for holding and locking these parts in their adjusted positions.

Heretofore in the practice of mounting carbon filaments upon leading-in wires the glass stem containing the leading-in wires has usually been held in position upon a supporting-base, upon which base the filaments are placed, after which the operator secured one 50 of the ends of said filament to a leading-in wire, permitted the paste to dry while the parts rested on the base, and then brought the other end of the filament into contact with the other leading-in wire and pasted the two 55 together. No means was provided to positively hold the filament and glass stem, with its leading-in wires, in fixed positions with relation to each other during this period.

Because of the substantially horizontal position of the parts referred to the paste used to connect the filament with the leading-in wires very frequently entered and remained between the wires and filament, whereby close contact of such parts and perfect joints there- 60 of was sometimes impossible because of the fact that the paste used is a somewhat imperfect conductor. Considerable dexterity on the part of the operator to thus manipulate the parts was required, and great care had to 65 be exercised to avoid breakage of the connection before the paste became hard.

By our improved machine the filament and leading-in wires are adjusted and mechanically held in proper relation to each other and the operator applies the paste, in this way having one hand free to move the carrier to advance the drum and bring another filament into position to be connected.

The carrier which we prefer to use is circular in form and rotates about an axis, so that as the filaments to be connected are advanced step by step the time consumed in making the circuit will enable the paste or connecting medium to become sufficiently 85 hard, and the operator may then complete the 90 operation of mounting the filament.

Our invention consists in the construction, arrangement, and combination of the several parts, all as hereinafter described and afterward pointed out in the claims.

5 In the drawings, 1 indicates the traveling carrier, shown in this instance as a hollow drum-like structure rotatably mounted on a spindle 2. It is obvious that our improved clamping devices could be otherwise mounted 10 and operate as well as when mounted on the drum 1. In fact, while the drum is intended to be individual to one operator it will be understood that by the use of a belt or other traveling conveyer for the clamping devices 15 a greater number of said clamping devices could be mounted thereon, so that two or more operators could work at the same machine—for instance, one operator inserting the pieces to be connected, another operator 20 pasting the first joint, a third operator pasting the second joint, the fourth operator removing the finished pieces, &c., the operators being spaced sufficiently far apart to permit the paste to harden. For these reasons we do 25 not wish to be understood as limiting our invention to a rotatable drum, except where such limitations may be expressed in the claims.

3 indicates a friction device, preferably in the form of a spring-pressed pivoted plate, 30 which engages the drum and serves to hold the same stationary when desired.

The filament-clamp preferably consists of a fixed jaw 4 upon its support, to which is pivotally connected the jaw 5, said jaw 5 having an extension whereby it may be readily opened, the jaw 5 being closed by the action of a spring 6. Jaws 4 and 5 are preferably elongated, so that the operator may in clamping one leg of a filament therebetween select 35 any point within the range of the jaws at which to hold the leg of the filament. In this manner the leg of the filament to be secured in position is adjustably clamped between the jaws at any point selected by the operator 40 within the range of said jaws.

The clamping device for the leading-in wires comprises the following:

8 indicates an apertured lug secured to the support, with which coöperates an apertured 50 lug 9, carrying an eye 10 at its outer end. A bolt 11 passes through the apertures of the lugs 8 and 9, said bolt being of smaller diameter than said apertures, permitting considerable play horizontally of the lug 9 with relation 55 to the supporting-lug 8. Washers 12 are strung on the bolt and a spring 13 is arranged between the head of the bolt and one of said washers, so as to exert friction on the parts to hold the lug 9 in proper position not only 60 to support the weight carried in the eye 10, but also to frictionally hold the lug 9 in adjusted positions. By adjusting the nut 14 on the end of the bolt the pressure of the spring may be regulated.

65 15 indicates a standard adjustably mounted

in the eye 10 and preferably locked in its vertically-adjusted positions by a set-screw 16. On the upper end of this standard 15 is a clamping-jaw 17, the socket in which may be semi-circular or angular, said clamping-jaw being held in position by binding-screws 18 and being provided with lugs 19, between which is mounted the movable companion clamping-jaw 20, whose socket may likewise be semicircular or angular. A handle 21 extends from the movable jaw 20, and a spring 22 is employed to force the jaw 20 inwardly toward its companion. This spring is shown as a torsion-spring coiled about the pivot-bolt of the movable jaw and having its free ends located under the binding-screws 18.

Because of the play between the lugs 8 and 9 the standard 15, mounted in said eye 10 on the lug 9, is free to move throughout a wide range practically in all directions to provide for any movement thereof necessary to bring the leading-in wires into contact with the legs of the filament. The dotted lines in Fig. 4 show said standard 15 with the clamping-jaws obliquely disposed with relation to the drum or belt 1 of that figure, and it will be apparent that glass tubes of various lengths may be provided for by the vertical adjustment of standard 15 in eye 10.

The leading-in wires 23 are usually platinum 95 and copper fused together, they being mounted in the closed end of a hollow glass holder whose other or outer end is flared or flanged, so as to be fused to the neck of the incandescent globe in a well-known manner. An anchor-wire 25 is also shown, which anchor-wire may be connected with or pasted to the loop of the filament while the several parts are held in the device herewith shown, if desired.

In operation the standard 15 is adjusted vertically to the proper position to accommodate the particular size of holders carrying the leading-in wires to which the filaments are to be connected. The glass holders are inserted between the clamping-jaws 17 and 20, with the leading-in wires uppermost, after which one leg of the carbon filament is introduced between the jaws 4 and 5, so that its end will overlap slightly the inner end of one of the leading-in wires to which it is to be connected. The standard 15 is now grasped by the operator, the yielding frictional contact between the lugs 8 and 9 permitting horizontal adjustment thereof in all directions, so that the operator can place the leading-in wire into contact with the clamped end of the carbon filament, the parts remaining in contact upon release of the standard. Paste is now applied to the contacting ends, and the traveling conveyer or drum, as the case may be, is advanced, so as to locate another set of clamping devices in front of the operator. This connection of one leg of the filament to one of the leading-in wires is continued in the instance of the clamping devices being mounted 130

on a rotatable drum until the parts first operated upon by the operator are again in position to receive attention, by which time the paste will have sufficiently hardened, and the liability to breakage of the joint is in this manner reduced to a minimum in further manipulation of the filament. The operator now releases the jaws 4 and 5 and rotates the glass holder so as to carry the connected ends of the filaments out of its former position, after which the free end of the filament is introduced between the jaws 4 and 5, so as to overlap slightly the other leading-in wire, and the operations before mentioned are repeated. It may be in the pasting of the second joint that it will only be necessary to rotate the glass holder in the clamping-jaws 17 and 20 to secure contact between the clamped end of the filament and the remaining leading-in wire; but if this will not effect proper engagement between the parts the lower clamping-jaw and its carried glass holder can be bodily adjusted, as before described.

Both handles of the movable jaws 5 and 20 are preferably so located and disposed that it is not necessary to grasp them between the fingers for the purpose of opening the jaws. The operator may exert this pressure by any convenient part of the hand to effect opening of the jaws, and thus leave the fingers and thumb free to manipulate a filament or the glass holder in their respective clamps.

By the term "leading-in wires" in the following claims we wish to be understood as including leading-in wires *per se* or, broadly, wires of any material mounted in glass holders, such as shown, or other supports, and by the term "spring-pressed jaws" we wish to be understood as including two pivoted jaws co-operating with each other or one pivoted and one stationary or fixed jaw.

We preferably provide means whereby heat is supplied at the point at which the filament is pasted to the leading-in wires in order that the paste can be rapidly dried. In the present embodiment of the invention the spindle 2 is supported in a stationary fitting 26 upon the end of a gas-pipe 27, which enters the rotatable drum or carrier 1, and burner-tubes 28 in communication with said gas-pipe project from said fitting. The peripheral wall of the drum is provided with suitable openings 29 in such position that they direct heated air from the drum to the paste upon the filaments and leading-in wires. A stationary housing 30 extends almost entirely about the periphery of the drum 1, and the filament-clamps and the clamps for the leading-in wires move in this housing, the heated air from the burner-tubes 28 entering said housing through the before-mentioned openings 29. The operator stands opposite the portion of the drum across which the housing does not extend, so that access can be readily had to the clamps upon the drum as the drum revolves. No burner-

tube projects toward the portion of the periphery of the drum about which the housing does not extend, and a deflector-plate 31 preferably extends across this portion of the drum, on the interior thereof, in order to prevent 70 the heated air from inconveniencing the operator, this deflector-plate being secured to the fitting 26, and therefore stationary.

It is obvious that the housing 30 may be connected with any suitable source of heat and 75 the heat for drying be supplied from an exterior source, in which case the burner-tubes 28 will not be required.

We are aware that minor changes in the construction, arrangement, and combination of 80 the several parts of our device can be made and substituted for those herein shown and described without in the least departing from the nature and principle of our invention.

Having thus described the invention, what 85 is claimed as new, and desired to be secured by Letters Patent, is—

1. In a device for securing incandescent-lamp filaments to leading-in wires, the combination with a movable carrier, of relatively 90 adjustable clamping devices mounted thereon for holding the filament and leading-in wires in position while they are being connected; substantially as described.

2. In a device for securing incandescent-lamp filaments to leading-in wires, the combination with a traveling carrier, of a plurality of pairs of relatively adjustable clamping devices arranged thereon for holding the filament and leading-in wires in position while 100 they are being connected; substantially as described.

3. In a device for securing incandescent-lamp filaments to leading-in wires, the combination with a traveling carrier, of means for 105 holding the carbon filament and leading-in wires in position while they are being connected, said means comprising independent relatively adjustable clamps; substantially as described.

4. In a device for securing incandescent-lamp filaments to leading-in wires, the combination with a rotatable carrier, of pairs of independent relatively adjustable clamping-jaws secured thereto for holding the carbon 115 filament and leading-in wires in position while they are being connected; substantially as described.

5. In a device for securing incandescent-lamp filaments to leading-in wires, the combination with a support, of clamping devices for holding the filament and the leading-in wires in position while they are being connected, one of said clamping devices being transversely adjustable with relation to the 120 axes of the leading-in wire; substantially as described.

6. In a device for securing incandescent-lamp filaments to leading-in wires, the combination with a support, of vertically-disposed 130

clamping devices for holding the filament and the leading-in wires in position while they are being connected, one of said clamping devices being horizontally adjustable with relation to the other; substantially as described.

7. In a device for securing incandescent-lamp filaments to leading-in wires, the combination with a support, of a pair of vertically-alined clamping devices, each of said devices being independently operable, and one of said devices being adjustable with respect to the other of said devices; substantially as described.

8. In a device for securing incandescent-lamp filaments to leading-in wires, the combination with a support, of a spring-actuated clamping device for the filament, a spring-actuated clamping device for the leading-in wires, means for adjusting the latter device vertically and locking it in such position, and frictional devices for holding said device in laterally-adjusted position; substantially as described.

9. In a device for securing incandescent-lamp filaments to leading-in wires, the combination with a support, of elongated spring-pressed clamping-jaws for holding the filament in position at any point within the range of said jaws, a companion clamping device, and means for laterally adjusting said clamping device for holding the leading-in wires in laterally-adjusted positions with respect to the clamping-jaws; substantially as described.

10. In a device for securing incandescent-lamp filaments to leading-in wires, the combination with a support, of a clamp for the filament and a clamp for the stem carrying the leading-in wires, said latter clamp comprising spring-pressed jaws mounted upon a vertically-adjustable standard, and frictional means for holding said standard in laterally-adjusted positions; substantially as described.

11. In a device for securing incandescent-lamp filaments to leading-in wires, the combination with a support, of an apertured lug arranged thereon, an apertured companion lug, means for creating friction between said two lugs whereby the latter lug may be held in laterally-adjusted positions, an eye carried by said last-mentioned lug, a standard vertically adjustable in said eye, and spring-pressed jaws carried upon the upper end of the standard; substantially as described.

12. In a device for securing incandescent-lamp filaments to leading-in wires, the combination with a movable carrier, of relatively adjustable clamping devices mounted thereon for holding the filament and leading-in wires in position while they are being connected, and a shell forming a closed heating-chamber into which the clamping devices and their carried parts are received; substantially as described.

13. In a device for securing incandescent-

lamp filaments to leading-in wires, the combination with a hollow rotatable carrier, a burner in said carrier, having escape-openings for the products of combustion, a shell encircling said carrier and forming a heating-chamber, and adjustable clamping devices mounted on the rotatable carrier for holding the filament and leading-in wires; substantially as described.

14. In a device for securing incandescent-lamp filaments to leading-in wires, the combination with a hollow rotatable carrier, a burner located therein, having escape-openings leading therefrom, a shell partially inclosing the carrier and forming a heating-chamber, and clamping devices on the carrier adapted to be moved into and out of the heating-chamber when the carrier is rotated; substantially as described.

15. In a device for securing incandescent-lamp filaments to leading-in wires, the combination with a rotatable hollow drum, of a stationary shell partially inclosing the same and forming a heating-chamber, burners within the drum, which drum is provided with escape-openings for the products of combustion, a deflector-plate in the drum for preventing escape of products of combustion through the openings opposite the portion not included within the heating-chamber, and clamping devices on the rotatable drum for holding the filament and leading-in wires in position while they are being connected; substantially as described.

16. In a device for securing incandescent-lamp filaments to leading-in wires, the combination with a rotatable circular drum formed hollow and having burners located therein, of a stationary encircling shell forming a heating-chamber open at one side to expose the clamping devices carried by the drum, and clamping devices on the drum for holding the filament and leading-in wires in position while they are being connected, said clamping devices being designed to travel through the heating-chamber; substantially as described.

17. In a device for securing incandescent-lamp filaments to leading-in wires, the combination with a pipe having burners extending from its upper end, a spindle projecting upwardly from the pipe, a hollow drum rotatably mounted on said spindle, a deflector-plate carried by the pipe, a stationary shell partially inclosing the periphery of the drum, and clamping devices mounted on the periphery of said drum; substantially as described.

In testimony whereof we hereunto affix our signatures, in the presence of two witnesses, this 30th day of June, 1903.
